UNITED STATES PATENT OFFICE.

ALWIN KURZ, OF BERLIN, GERMANY, ASSIGNOR TO BAU- UND HANDELSUNTER-
NEHMUNGEN G. M. B. H., OF BERLIN, GERMANY.

APPARATUS FOR MAKING SUNK STAMPINGS.

1,182,573.

Specification of Letters Patent.

Patented May 9, 1916.

Application filed December 10, 1913. Serial No. 805,760.

To all whom it may concern:

Be it known that I, ALWIN KURZ, engraver, subject of Germany, residing at No. 70 Friedenstrasse, in the city of Berlin, 5 German Empire, have invented new and useful Improvements in Apparatus for Making Sunk Stampings; and I do hereby declare the following to be a full, clear, and exact description of the same.

10 My invention relates to the mechanical production of metallic printing plates and has for its object to impart to the characters or the like which are thus produced the appearance of work cut by hand.

15 Metallic printing plates produced by mechanical means, as is well known is effected by means of dies or letter punches, which bear the character (for instance a letter) at one end, and are forced into the 20 metal plate by the pressure of a ram. To maintain the requisite distance between the individual impressions it is necessary to displace either the printing plate with relation to the stamping device, or conversely, the 25 stamping device with relation to the printing plate.

In order to maintain the intervals between the individual impressions as uniform as possible and thus obtain a uniform and 30 even-looking result, the procedure adopted in punching the individual characters in succession according to the method forming the subject of the present invention, is to displace the printing plate or stamping die 35 laterally through a distance corresponding with that to which the characters to be stamped project sidewise beyond a middle plane (preferably the middle plane of the punch provided with such characters).

40 Consequently, the distance between two adjacent characters will result from the sum of the distances to which two successive characters project, facing each other, from the said middle plane, plus the free space 45 left between the two characters.

The new method of operating affords the possibility of using dies of equal width for the various characters, even when these latter are asymmetrical, and nevertheless of 50 maintaining an exactly uniform distance between the separate characters.

To enable the relative displacement between the printing plate and stamping die to be properly effected in accordance with 55 the invention, the apparatus used for stamp-

ing is preferably equipped with adjustable stops, which determine the proper relative positions of the printing plate and stamping die at the moment the character is being stamped.

The annexed drawing illustrates one form of apparatus suitable for carrying out the invention.

Figure 1 is a front elevation and Fig. 3 a longitudinal section of the apparatus, 65 while Fig. 2 is a plan of a rack slide, the press spindle being shown in section. Figs. 4 and 5 represent the adjusting device in section and end elevation. Figs. 6, 7 and 8 are perspective views of detached parts 70 of the adjusting device. Fig. 9 shows a detachable stop in the preferred form and Fig. 10 shows a stop to be fastened to the slide for co-operating with the detachable stops. Fig. 11 is a diagram illustrating how 75 the detachable stops of the adjusting device are determined according to the kind of character to be stamped.

The base plate *b* can be pushed to and fro, 80 transversely in the lower part of the yoke *a*, by means of the handle *d*. In the upper part of the yoke *a* the slide *c* runs at right angles to the direction of movement of the base plate *b*. The press spindle *e*, carrying the ram *f*, can be moved up and down in the 85 slide *c* by rotating the ball-tipped arm *s*. The downward movement of the spindle *e* forces the type *h*, which is inserted in a guide *g*, into the metallic printing plate *i* which is secured on the base plate *b*. The 90 guide *g* is screwed fast on the slide *c* in such a position that the axis of the spindle *e* lies in the central plane of the guide. The adjusting device for insuring the correct distance between the characters to be stamped 95 consists in the example shown of a sliding member *m*, the foot member *m*¹ of which is adapted to be displaced in the groove *n* of the yoke *a* in a direction parallel to the direction of movement of the slide *c*. This 100 sliding member *m* carries a mandrel *o* on which are slipped the stops *p*. On the slide *c* is screwed the stop *q* against which the member *m* is pushed at the beginning of the stamping operation in such a way that the stop *q* bears against the outermost washer *p* slipped on the mandrel *o*. This done, the member *m* is clamped by means of the eccentric *l*. This eccentric pin *l* is lodged in the bore of the gudgeon *m*² by means of 105 110

which the foot m^1 engages in the sliding member m . Consequently, by turning the handle l^1 of the eccentric, the foot m^1 and the member m are pressed firmly against the guide in the yoke a . It may be understood that the mandrel o could be attached to the slide c and the stop q to the sliding member m . After each operation of stamping a character in the plate, the washers p determining the distance between the impressed character and the one next following are drawn off the mandrel, and the slide c is displaced by a distance equal to the intermediate space thus formed.

To enable the depth of the impression of the type in the metallic printing plate to be accurately fixed, a scale t is provided on the spindle e and a pointer u on the slide c . For the prevention of errors, a loose pointer v is arranged over the scale t and is set against that part of the scale to which the pointer u is intended to be turned. The slide c is moved by means of pinions x which engage in the racks y provided on the slide. The pinions x are secured on the shaft z mounted in the bearings I^a and I^b . The spacing of the lines of the impression is effected by displacing the base plate b , the exact adjustment being controlled by means of a graduated scale II secured on the base plate b and by a pointer III on the yoke a . When in the right position the base plate is clamped by means of the eccentric IV .

The thickness or width of the metal washers p is determined in the following manner: The individual characters, letters for example, are cut in the known manner on the end surface of a type bar h . According to the kind of letter, the individual parts of same project laterally for a certain distance sidewise from an imaginary central plane, for instance the central plane of the type bar. As shown in Fig. 11, the letter B for example would project sideward from the dotted line indicating the central plane, leftward for the distance $1'$ and rightward for the distance $1''$. The letter E extends leftward for the distance $2'$ and rightward for the distance $2''$ in a lateral direction, and so on. If it be desired to stamp the letters B and E in succession, the die is pushed from the central line of the letter B as far as the central line of the letter E. The distance moved is the sum of the two adjacent projections, that is to say $1''$ and $2'$, plus the free space s' between the two letters. If now the washers be of such a thickness as is equal to the lateral projection of the letter toward the one side, plus half the width of the space, then the distances separating the individual characters can be fixed by arranging these washers in successive order. If, for instance, the word "BERLIN" is to be stamped in the plate, the grouping of

the washers according to Fig. 11 is as follows: For the first impression, the pressure member must be in position over the central plane of the letter B; for the next impression it must be over the central plane of the letter E, and so on. Therefore, for the first letter of the word, the right hand washer must be inserted, and the left hand washer for the final letter, while for the intermediate letters both washers must be slipped on. Hence, in Fig. 11, the washer 1 corresponds to the right half of the letter B. Then follow the washers 2 to 9, two each for the letters E R L I, and the washer 10 for the left half of the letter N, the thickness of the washer 1 being, according to the above statement, equal to $1''$ plus $\frac{s'}{2}$, that of washer 2 equal to $2'$ plus $\frac{s'}{2}$, that of washer 3 equal to $2''$ plus $\frac{s'}{2}$, and so on.

The stamping of the word "BERLIN" is effected as follows: The slide c is moved so that the punch is exactly over that part of the printing plate i where the letter B is to be stamped. The ten washers are slipped on to the mandrel o of the sliding member m in the manner already explained, so that the washer 1 is in front, on the right hand side in Fig. 2. The member m is then moved so far that the washer 1 bears against the stop q , and is clamped in this position. The type bar carrying the letter B is then inserted into the guide g and the letter B is stamped in the plate by turning the spindle e . The two washers 1, 2 are then taken off, and the slide c is moved so that the stop q bears against the washer 3, whereupon the type bar bearing the letter B is replaced in the guide g by the bar provided with the letter E, and so on.

What I claim and desire to secure by Letters Patent of the United States is:—

1. In an apparatus for making sunk stampings, the combination of a support; an adjustable member and a type operating member carried on said support; and loose detachable pieces interposed between said members.

2. In an apparatus for making sunk stampings, the combination of a support; an adjustable member and a type operating member carried on said support; and pieces interposed between said members and corresponding in width to distances between a given line of the letter and the line midway between such letter and the adjacent letter of the respective letters to be stamped.

3. In an apparatus for making sunk stampings, the combination of a base; a support held thereover; a slide on said support and adapted to guide type; means for press-

ing the type toward the base; a sliding member adjustably secured to the support; and a plurality of pieces interposed between said member and slide.

5 4. In an apparatus for making sunk stampings, the combination of a base; a support held thereover; a slide on said support and adapted to guide type; means for pressing the type toward the base; a sliding member adjustably secured to the support; and a plurality of pieces interposed between said member and slide, and corresponding respectively in width to the distances between the median line of the letter 10 and the line midway between such letter and the adjacent letter of the letters to be stamped.

5 5. In an apparatus for making sunk stampings, the combination of a base; a support supported over said base; a slide slidably mounted on said support and provided with a guide for receiving a type; means for pressing the type toward said base; a sliding member adjustably supported on 20 said support; a washer carrying device on said member; and washers on said device between said member and slide and corresponding in width respectively to the distance between the center of resistance of respectively the types and the point midway 25 between the types and the adjacent type.

5 6. In an apparatus for making sunk stampings, the combination of a yoke; a base plate supported below the yoke; a slide 30 slidably mounted on the yoke and over the base plate; a guide secured to the lower part of the slide; a plurality of types adapted to be interchangeably received in the guide; means carried by the slide for press-

ing the type toward the base plate; a stop 40 secured on said slide and having a hole therein; a mandrel adapted to be received by said hole; a sliding member adjustably secured on said yoke and supporting said mandrel and a plurality of washers on said 45 mandrel between said stop and member.

7. In an apparatus for making sunk stampings from types having characters projecting different distances from the central plane of the type bar, the combination 50 of a pair of relatively movable parts; a type operating means on one of said parts; and means for limiting the movement between said parts to increments equal respectively to the variable distances between the central planes of the types to be stamped. 55

8. Apparatus for making sunk stampings in printing plates by means of type bars which are provided with the characters to be impressed in the plate comprising in 60 combination a slide movable relatively to the printing plate which slide carries a guide for the type bars, means for displacing the type bar perpendicularly to the plate, a sliding member which is adapted to be displaced parallel with the direction of movement of the slide, and detachable stops for determining the relative position of the slide and the said sliding member, substantially as set forth. 65

In testimony whereof, I have signed my name to this specification in the presence of two subscribing witnesses.
